UNITED STATES PATENT OFFICE.

FERDINAND GELTZ, OF BEURIG, NEAR SAARBURG, GERMANY.

TOBACCO-PIPE.

No. 895,626.

Specification of Letters Patent.

Patented Aug. 11, 1908.

Application filed May 15, 1908. Serial No. 433,138.

To all whom it may concern:

Be it known that I, FERDINAND GELTZ, königlicher forstmeister, subject of the King of Prussia, residing at Beurig, near Saarburg, 5 (Prussia,) Germany, have invented new and useful Improvements in Tobacco-Pipes, of which the following is a specification.

This invention relates to a tobacco-pipe with a smoke-tube reaching uninterruptedly 10 from the mouthpiece almost to the bowl, and separate exterior chambers for the reception of nicotin and saliva, the purpose of this arrangement being to keep the smoke as far as possible separated from the saliva and nicotin.

15 The accompanying drawings show the invention in one form of construction. In the projecting part (a) of the bowl (b) is pierced the smoke-channel (d) and also an additional channel (c) for the reception of 20 the nicotin, one end opening directly below the bowl of the pipe, the other end being connected with the smoke-tube (e) so that smoke can be drawn from the bowl directly into the mouth without passing through the nicotin- 25 chamber.

To guard against the entrance of ashes into the smoke-channel (d) the opening of it is 30 covered with a sheet of perforated metal (f) which also guides the drops of falling nicotin past the opening and into the reservoir beneath. The object of this arrangement is to separate the lighter and more volatile gases from the nicotin almost directly on leaving the bowl, so that the taste of the 35 smoke may not be influenced, particular care being taken that the smoke does not pass over the surface of the already separated nicotin.

The principal object of this arrangement 40 is the separation of smoke and nicotin, the second object is to keep the smoke as far as possible from contact with saliva in the interior of the pipe.

The smoke-tube (e) is surrounded by a 45 chamber divided into two compartments (h) and (i) by the diagonal partition (g), the upper part being closed by a funnel (k) in which an opening (l), opposite to the outlet (m) allows the saliva to fall onto the diagonal 50 partition (g) passing thence through the outlet (m) into the lower part of the chamber, whence it can be emptied through the stopped opening (n) by help of the funnel formed by the diagonal partition (g) with the sides of 55 the chamber. This arrangement insures the most perfect separation of the saliva from

the smoke-tube and guards moreover against its flowing back into the stem of the pipe, no matter in what position the pipe may happen to be; for even if the pipe is completely inverted the saliva is either led by the diagonal partition into the lower chamber or kept in the upper by means of the angle formed by the funnel, even though present in large quantities. The invention would however 60 be incomplete if the smoke-tube were not also closed against the entry of saliva. This is provided by means of a hood arranged above the collecting point of the saliva and set onto the smoke-tube by means of its tu- 65 bular lower end (o), narrowing above to a waist and spreading out beyond into a globe, the upper extremity of which terminates in a tube (q) which narrows suddenly and is bent to one side. 70

The channel (d) can be modified in the form of a cavity as it is indicated by the dotted lines (r) for collecting the ashes which have penetrated eventually the perforated sheet (f). 75

What I claim and desire to secure by Letters Patent is:

1. A tobacco pipe comprising a bowl having a channel for the nicotin extending from its lower part, and a smoke channel 85 extending from the upper part of the nicotin channel downwardly to the exterior of the bowl, and a stem having a smoke channel therein communicating with the smoke channel in the bowl. 90

2. A tobacco pipe comprising a bowl having a projecting lower part, a stem having a smoke channel therein and a socket adapted to receive said projecting part, said projecting part having a nicotin channel extending 95 vertically therethrough and connecting the bottom of the bowl with the socket, a smoke channel extending from the upper part of the nicotin channel downwardly at an angle to the exterior of said projecting part, and communicating with the smoke channel in the stem. 100

3. A tobacco pipe comprising a bowl, a smoke tube connected with the bowl, a casing surrounding said smoke tube, a diagonal 105 partition in said casing dividing the same into two chambers, said partition having an opening at the lower end thereof, said casing having a controlled opening therein under the partition and adjacent the upper end 110 thereof, a funnel in the upper chamber having its opening arranged diagonally and ad-

5 jacent the upper part of the partition, the smoke tube opening into the upper part of the casing above the funnel, and a mouth piece connected to the upper part of the casing.

4. A tobacco pipe comprising a bowl, a smoke tube connected to the bowl, a casing surrounding the tube, collecting means in the casing for the saliva, a hood on the smoke tube above said collecting means, and a bent tube connected to said hood.

10 5. A tobacco pipe comprising a bowl, a smoke tube connected thereto, a casing surrounding the upper part of the tube, saliva collecting means for said casing, a hood on

15 the upper part of said tube and within the casing, said hood consisting of a globe having a tubular lower projecting portion for engaging the end of the tube, said portion narrowing upwards to a waist and spreading out again where it connects with the globe, and a narrow tube connected to the tube of the globe and bent to one side.

20 In testimony whereof I have signed my name to this specification in the presence of 25 two subscribing witnesses.

FERDINAND GELTZ.
